ATTORNEY.

UNITED STATES PATENT OFFICE.

EDWIN BURCH, OF BALTIMORE, MARYLAND.

RAZOR-WIPER.

1,334,886.

Specification of Letters Patent. Patented Mar. 23, 1920.

Application filed September 19, 1919. Serial No. 324,756.

To all whom it may concern:

Be it known that I, EDWIN BURCH, a citizen of the United States, residing at Baltimore, State of Maryland, have invented new and useful Improvements in Razor-Wipers, of which the following is a specification.

The object of my present invention is the provision of an inexpensive device designed to hold shaving paper against placement under the action of an electric fan or other draft of air, and also designed to enable a barber to expeditiously and thoroughly wipe a razor with one hand.

To the attainment of the foregoing, the invention will be fully understood from the following description and claims when the same are read in connection with the drawings, accompanying and forming part of this specification, in which:

20 Figure 1 is a perspective of a razor-wiping device constituting the best practical embodiment of my invention of which I am cognizant.

Fig. 2 is a transverse central section taken 25 through the device, and illustrating the manner in which several sheets of paper are secured to the device and in superimposed position upon the anti-friction balls or rolls thereof.

30 Similar numerals of reference designate corresponding parts in both views of the drawings.

Among other elements my novel device comprises a main frame 1 of general 35 rectangular contour and preferably formed of wire. The piece of wire terminates in inwardly directed arms 2 which are spaced apart and arranged, by preference, in parallelism, and are provided at their inner 40 ends with upstanding barbs or prongs 3.

Pivoted to the frame 1 at opposite sides of the arms 2, as indicated by 4, is a paper-retaining bail 5.

Mounted upon and by preference freely 45 rotatable about one side bar and the end bars of the frame 1 are rubber rolls 6 which are preferably in the form of balls, as illustrated.

In the practical use of my device the de-

vice is placed upon the breast of a person 50 in a barber's chair, and shaving paper is impaled upon the barbs 3, after which the bail 5 is swung down upon the shaving paper. When desired, the bail 5 may be used to press the shaving paper down upon the 55 barbs 3, and in any event the said bail 5 serves to prevent casual displacement of the shaving paper and to retain the same in superimposed position upon the cushioning means afforded by rolls 6. 60

Manifestly my novel device enables a barber by manipulating a razor with one hand over the shaving paper, to adequately wipe the razor and in this connection it will be appreciated that the capacity of the rolls 65 6 to freely rotate, will lessen the liability of the shaving paper being displaced by the wiping engagement of the razor blade therewith. It is to be understood, however, in this connection that the chief function of 70 the rolls 6 is a cushioning one, to preclude injury to the razor blade, when the same is wiped across the shaving paper.

While designed more particularly for use in a barber's shop, the wiper may be 75 used to advantage by individuals who shave themselves; the wiper in that case being positioned upon a dressing table or other support.

Having described my invention, what I 80 claim and desire to secure by Letters-Patent, is:

1. A razor wiping device comprising a frame of wire having inwardly directed spaced arms that terminate in upstanding 85 barbs, a bail pivotally connected to the side of the frame at opposite sides of the pair of arms, and rolls of yielding material mounted on the frame.

2. A razor wiping device comprising a 90 frame having upstanding means for holding shaving paper, cushioning means on the frame and opposite said holding means, and means to retain shaving paper upon the holding means, and the cushioning means. 95

In testimony whereof I affix my signature.

EDWIN BURCH.
